UNITED STATES PATENT OFFICE.

CHARLES A. DEARBORN, OF NEW YORK, N. Y.

BLINDSTITCH SEWING MACHINE.

Original application filed December 23, 1924, Serial No. 757,653. Divided and this application filed July 22, 1925. Serial No. 45,292.

The present invention relates to blind stitch sewing machines of the general type illustrated in my prior Patents No. 639,669, dated December 19th, 1899, and No. 814,025, dated March 6th, 1906. The present application is a division of my application Serial No. 757,653, filed December 23rd, 1924.

The object of the present invention is to improve and modify the work handling mechanism of this type of sewing machine to adapt it more especially for felling piped edges of seams. The presser foot has in the past usually been a single rigidly supported member against which the work is pressed by a yielding work support. In the new machine the presser foot is divided, the main part at the left of the ridge forming rib above the work support being fixed, while the auxiliary part at the right of the ridge forming rib is mounted upon a spring supported arm to yield laterally away from the line of stitching under the strain of an extra heavy part of the work such as is encountered with heavy cross seams. The fixed and yielding portions of the presser foot separate in the vertical plane of the ridge forming disk which determines the line of stitching. The spring acting upon the yielding portion of the presser foot tends to move the same toward the fixed portion of the presser foot and its normal relation is determined by a conical adjusting screw.

The fixed portion of the presser foot is formed with an upstanding rib which engages the inwardly presented piped edge of the seam to hold the piping out of the path of the narrow portion of the reciprocating feed dog, which in this type of machine engages the work on its upper face. This upstanding rib is transversely grooved or recessed in the path of the needle.

The fixed portion of the presser foot also carries a spring pressed dog which engages the work on the left side of the ridge forming rib to thereby hold the goods down closely to the rib to bring the line of stitches, i. e.—the line in which the point of the needle emerges in the sewing operation, as far as possible beneath the piped edge.

In order that the invention may be fully understood it will first be described with reference to the accompanying drawings and

afterwards pointed out more particularly in the annexed claims.

In said drawings:

Fig. 1 is a side elevation of the improved blind stitch felling machine;

Fig. 2 is a plan view of the same with the sewing machine arm, the needle shaft, and other parts broken away for the sake of clearness;

Fig. 3 is a detail front elevation of the stitch forming mechanism, showing also the work supporting mechanism in section;

Fig. 3^a is a detail side elevation of parts shown in Fig. 3;

Fig. 4 is a detail view similar to Fig. 3; showing the needle in its retracted position;

Fig. 5 is a vertical longitudinal sectional view taken on the line 5—5 of Fig. 3;

Fig. 6 is a detail horizontal sectional view taken on the line 6—6 of Fig. 1;

Fig. 7 is a detail transverse sectional view taken on the line 7—7 of Fig. 1.

1 is the main frame of a sewing machine of the type set forth in my above named patents and 2 is the sewing machine arm projecting forwardly from the main bearing 3 to a point above and adjacent to a work support presently to be referred to. The frame 1 has an upwardly presented rigid arm 5 in which is rigidly mounted the horizontal bolt 6 upon which is journalled a rocking frame 7, which projects rearwardly and forms a U-shaped yoke carrying the ridge forming disk 85 journalled in it at 11 and the independently yielding working supporting plates 12 pivoted at 13 upon arms 14 journalled at 15 and controlled by springs 16.

The U-shaped frame 7 has a downwardly projecting arm 20 connected at 21 by a strong contractile spring 22 attached at its inner end to a flange 23 of the machine frame 1.

An adjusting screw 25 is threaded in lugs 26 of the machine frame and engages at its forward end with the arm 20 and is provided at its rear end with a milled hand operated head 27 by which the screw can be adjusted. The head 27 has a bevelled face 100 marked off in a suitable scale to indicate at a glance the adjusted position of the screw 25. Adjacent to the head 27 is a grooved cylindrical portion 29 with which

engages a spring detent 30 mounted upon a pin 31 of the machine frame and serving to hold the adjusting screw 25 against accidental displacement. A second screw 33 is adjustably mounted in the lug 26 in the path of the arm 20 to limit the movement of the arm in one direction under the action of the spring 22.

35 is the main fixed portion of the presser foot secured to the lower end of a plate 36 which is adjustably mounted on a vertical face of the machine arm 2 by means of machine screws 37. This fixed portion of the presser foot is mounted above the work support to the left of the ridge forming rib and carries additional elements hereinafter referred to.

66 is a shoe formed on the lower end of plate 67 secured to a vertical face of machine arm 2 by screws 68, see Fig. 3^a. The shoe 66 is fixed in the horizontal plane of the presser foot alongside of the reciprocating feed dog 70, hereinafter referred to, and serves to confine the work downwardly adjacent to the feed.

40 is the auxiliary laterally adjustable portion of the presser foot consisting of a short forwardly presented blade mounted upon the lower end of a curved lever 41 pivoted to the sewing machine arm by means of a screw 42 and having an arm 43 projecting to the left above a limiting stop 44, which confines the extent of movement of the auxiliary presser foot member away from the fixed member. A contractile spring 45 engages the arm 43 and connects with an arm 46 upon the machine frame for giving the presser foot member 40 a spring tendency to move inwardly toward the vertical plane of the ridge forming disk 10. This spring motion of the auxiliary presser foot is limited by a conical adjusting screw 50 threaded in the machine arm and engaging arm 43 of lever 41. From this structure it will be observed that this auxiliary portion 40 of the presser foot is free to yield outwardly against the action of spring 45 up to the limit of stop 44. Laterally yielding member 40 is presented directly in front of feed dog 70 and above the right-hand work supporting plate 12. Member 40 cooperates with fixed shoe 66 in resisting upward pressure of the work passing over the work support.

60 is the curved needle carried by the arm 55 61 adjustably mounted upon the needle rock shaft 62 driven by the rock arm 63, the universal joint link 64 and eccentric on the main drive shaft 65 in the same manner as previously employed in this type of machine. The needle reciprocates in guide grooves formed in the concave upper faces of the main and auxiliary portions of the presser foot 35 and 40.

70 is the two part reciprocating upper feed secured by screws 71 to the forward

projection of the oscillating reciprocating feed bar 75 which is driven at its rear end by eccentric connection 76 with the main shaft of the machine and supported between its ends by a headed guide pin 77 projecting laterally from a lug of the machine arm and adjustably secured therein by set screw 78. This pin 77 passes through a slot in the feed bar 75 and confines it to its vertical plane of operation. The feed bar 75 has a universal joint 80 with a link 81 which in turn has a universal joint 82 with a rock arm 83 adjustably mounted upon the needle rock shaft 62 by means of set screw 84. The upper feed member 70, shown best in Figures 2, 3 and 3^a of the drawings, is a broad curved plate having two parallel downwardly presented toothed edges which engage the upper surface of the work above the two supporting plates 12, one serrated feed edge being arranged above and in the vertical longitudinal plane of each plate 12.

90 is the looper proper adjustably mounted in the forward end of a cylindrical looper bar 91 which is secured at its rear end to a yoke 92 trunnioned upon an eccentric lug 93 of a bearing sleeve 94, which is journalled upon an angularly set crank pin 95 of the crank disk 96 carried by the main shaft 65 of the machine. This angularly set crank with universal joint connection with the looper rod is similar to that shown in my above named patents and forms part of the present invention excepting only as an essential part of the mechanism for operating the looper in the manner hereinafter described.

The looper bar 91 passes freely through aligned bearing sleeves 100 of a floating bearing frame 101 which is formed at its forward end with a bearing yoke 102 freely pivoted at 103 upon the lower end of a vertical pivot pin 105, which turns freely in bearing opening 106 formed eccentrically in the cylindrical bearing block 107 which is mounted adjustably in the split socket 108 of the sewing machine arm. This bearing block 107 is formed with a squared upper end by which it can be turned in the split socket of the machine frame and secured in the desired adjusted position by the set screw 110. By adjusting the block 107 the vertical pivot pin 105 can be shifted laterally and forwardly and backwardly for accurately positioning the point of the looper to cause it to properly cooperate with the needle. The pivot pin 105 is confined in the bearing block 107 by means of the headed set screw 109 threaded in the upper end of pin 105 and engaging the upper end of bearing block 107.

The main fixed portion 35 of the presser foot is provided with an upstanding rib 120 upon its inner edge in which is formed a needle receiving recess or grooves 121 corre-

sponding in position with the transverse groove 122 in the upper face of foot member 35. A deep longitudinal groove 125 is formed in foot member 35 for the operation of the looper 90.

130 is a cloth engaging member pivoted in the slotted forward end of presser foot 35 and engaged by a spring 131 for holding its cloth engaging downwardly presented end 10 alongside of the ridge forming disk 10.

When the work is placed in the machine, the work support is depressed usually by a foot pedal (not shown) connected with U-shaped frame 7 and the work inserted between the supporting plates 12 and the two part presser foot, the heavy or hemmed portion of the work being presented at the right of the ridge forming disk beneath the laterally yielding foot member 40. The edge of the seam, which is commonly piped, is presented over the ridge forming disk 10 and the work at the left is pressed downwardly by the spring pressed plate or dog 130 to confine the work as closely as possible upon the disk 10 to thereby maintain the line of stitches closely beneath the piped edge of the seam. The upstanding rib 120 diverts the piped edge of the seam slightly toward the disk 10 to hold it out of the way of the top feed member which engages the work parallel with the longitudinal groove 125.

The improved looper mechanism is more fully described and is covered by the claims in my above named original application, Ser. No. 757,653.

The structure of the presser foot with the auxiliary laterally yielding portion is an important novel feature. This yielding portion of the presser foot takes care of unusually heavy parts of the work passing between the work support and presser foot. For instance, the passage of cross-seams on heavy material will cause the auxiliary presser foot member to yield outwardly while the stitching operation takes place. This laterally yielding foot member can also be set by the adjustment of the conical screw 50 to suit different grades of work or thicknesses of material, it being clear that when operating upon thin material foot member 40 would naturally operate closer to the line of stitching than it would when operating upon heavier material. The change to suit a particular grade of work can readily be effected by the operator.

The fixed shoe 66 in rear of the presser foot member 40 serves to confine the work above the right-hand work supporting plate 12 under the action of the feed dog, stripping the work from the feed dog as it completes its feeding stroke and starts forwardly for new engagement with the work.

I claim:

1. In a sewing machine, the combination of a work support carrying a ridge-forming

disk, a presser foot, and stitch forming mechanism operating above said presser foot, with a spring-pressed dog mounted upon said presser foot and projecting alongside of said ridge-forming disk for pressing downwardly upon the work passing over said disk.

2. In a sewing machine, the combination of a work support carrying a ridge-forming disk, a presser foot, stitch forming mechanism operating above said presser foot, and suitable feeding means, with a spring-pressed dog mounted upon said presser foot and formed with a flange which projects alongside of said ridge-forming disk parallel with the direction of feed for pressing downwardly upon the work passing over said disk.

3. In a sewing machine, the combination with a yieldingly mounted work support, of a two-part presser foot above said work support, said presser foot being divided upon the line of stitching and having one part fixed and the other part movable laterally toward and away from the line of stitching, suitable work feeding means, stitch forming mechanism including a needle, and an upstanding longitudinal rib upon the fixed part of said presser foot adjacent to the line of stitching, said rib being formed with a transverse notch to receive the needle.

4. In a sewing machine, the combination with a work support and suitable stitch forming mechanism, of a two-part presser foot divided upon the line of stitching, one presser foot part being rigid and the other presser foot part being mounted to yield laterally away from the line of stitching.

5. In a sewing machine, the combination with a work support and suitable stitch forming mechanism, of a two-part presser foot divided upon the line of stitching, the presser foot part on one side of the line of stitching being fixed, an upstanding rib arranged longitudinally upon said fixed presser foot part adjacent to the line of stitching adapted to engage and guide the turned over edge of a seam, the auxiliary presser foot part on the other side of the line of stitching being adjustable, and a spring for yieldingly holding said auxiliary part in operative position.

6. In a sewing machine, the combination with a work support and suitable stitch forming mechanism, of a two-part presser foot divided upon the line of stitching, one presser foot part being fixed with relation to the line of stitching, and the other presser foot part being movable laterally toward and away from the line of stitching, a spring acting upon said movable presser foot part, and manually operated means for adjusting said movable foot part and determining its operative relation to the line of stitching.

7. In a sewing machine, the combination

- 4
- with a yielding work support, and suitable stitch forming mechanism, of a presser foot divided in the line of stitching, a pivoted lever supporting part of said presser foot 5 on one side of the line of stitching, a spring engaging said lever for yieldingly holding said presser foot part in position, and an adjustable stop for determining the operative position of said presser foot part.
8. In a sewing machine, the combination with a yielding work support carrying a ridge-forming disk, suitable stitch forming mechanism, and suitable work feeding means, of a presser foot divided in the plane 15 of said ridge-forming disk, a pivotally mounted lever carrying the part of said presser foot on one side of said disk, a spring engaging said lever for yieldingly holding said presser foot part in position, and an 20 adjustable stop for determining the operative position of said presser foot part with relation to said disk.
9. In a sewing machine, the combination with a yielding work support carrying a ridge-forming disk and independent work 25 supporting plates on opposite sides of said disk, of a feed dog operating above said supporting plates, a fixed shoe above one of said plates adjacent to said feed dog, 30 a laterally movable presser foot member mounted above the work supporting plate in front of said shoe, and a fixed presser foot member above the other work supporting plate on the opposite side of said disk.
10. In a sewing machine, the combination 35 with a yielding work support, and suitable stitch forming mechanism, of a presser foot divided in the line of stitching, a pivoted lever supporting part of said presser foot 40 on one side of the line of stitching, a spring engaging said lever for yieldingly holding said presser foot part in position, and an adjustably mounted cone-headed screw 45 engaging said lever to determine the position of the presser foot part carried thereby.
11. In a sewing machine, the combination of a frame, a work support, a presser foot, and suitable stitch forming mechanism including a needle rock shaft, with a feed dog operating above the work support, a feed 50 bar upon which said feed dog is mounted, a rock arm upon said rock shaft, a link having universal joint connections with said feed bar and said rock arm, and means for reciprocating said feed bar.
12. In a sewing machine, the combination of a frame, a work support, a presser foot, and suitable stitch forming mechanism including a needle rock shaft, with a feed dog operating above the work support, a feed 55 bar upon which said feed dog is mounted, eccentric drive mechanism engaging the rear end of said feed bar, a guide engaging said feed bar between the ends, a rock arm upon said needle rock shaft, and a connecting link having universal joint connections with said feed bar and said rock arm.

CHARLES A. DEARBORN.
